UNITED STATES PATENT OFFICE.

JOSEPH E. KENNEDY, OF NEW YORK, N. Y.

CRUSHING AND PULVERIZING MACHINE.

1,090,216.

Specification of Letters Patent. Patented Mar. 17, 1914.

Application filed August 5, 1907. Serial No. 387,067.

To all whom it may concern:

Be it known that I, JOSEPH E. KENNEDY, a citizen of the United States, residing in the borough of Manhattan, city, county, and State of New York, have invented certain new and useful Improvements in Crushing and Pulverizing Machines, of which the following is a specification.

My improvements relate to crushing and pulverizing mechanism of the gyratory type, and are designed to afford a substantial compact structure of relatively light weight, in which the shaft is suspended at its upper end upon an adjustable bearing, and in which the change of inclination consequent upon the adjustment of the shaft is compensated for by an eccentric bearing of peculiar construction in that it is free to adapt itself to the alignment of the shaft.

My invention also includes other special features in the construction and arrangement of parts hereinafter described and claimed.

In the accompanying drawings, Figure 1, is a central vertical sectional elevation of my improved apparatus; Fig. 2, is a section upon plane of line 2-2 Fig. 1; Fig. 3, a view similar to Fig. 2, showing a modification.

In general operation and arrangement of parts my apparatus is essentially the same as others of the gyratory class, consisting of a truncated conical crushing head *a*, rigidly secured to the shaft *A*, and gyrating in an oppositely inclined convex crushing chamber *b*, from which the reduced material escapes into the chute chamber *c*.

1, is an annular shoulder or collar keyed or otherwise rigidly secured to the upper end of the shaft *A*. This collar 1, rests upon an annular bearing 2, which rests in turn upon an adjustable support 3, mounted in the upper frame plate *d*. Obviously the most expedient way of making the support 3, adjustable is to form it with a peripheral male screw for engagement with a female screw thread on the upper frame plate *d*, or on the sleeve *d'*, inserted in the latter as shown in the drawings, although I do not limit myself in this particular—the essential feature in this respect being the provision of suitable means for effecting the vertical adjustment of the annular bearing 2.

The lower portion of the shaft *A*, is journaled in the bore 4, of the eccentric bearing 5, in the usual manner, but the ec-

centric bearing itself is of special construction. Peripherally as related to its axes of rotation it is of convex form, being uniformly curved in the arc of a circle, and is seated in a correspondingly curved cavity 6, in the sleeve 7, to which the driving gear 8, is secured. The principle involved is that of the ball and socket, but the change in inclination of the longitudinal axis of the shaft within the prescribed or desired limits of adjustment are so slight that it is not necessary in practice to resort to the spheroidal form, which would be objectionable on account of the space involved. While thus free to adapt itself to the inclination of the shaft *A*, the eccentric bearing 5, is held against lateral movement in its seat 6, by one or more keys 7, or equivalent mechanical expedients, by which it is coupled to the sleeve 7, so as to rotate therewith while free to adapt itself axially with relation to the longitudinal axis of the shaft.

The driving gear 8, is rotated by means of the pinion *p*, upon the power shaft *P*; and the apparatus is provided with the usual dust guards, &c.

The sleeve 7, is made in two or more parts to admit of the seating of the axially convex eccentric bearing 5, the parts of the sleeve being rigidly secured together, and to the driving gear 8. The essential feature being the axial convexity of the eccentric bearing 5, with relation to its seat 6, in the sleeve 7, it is obvious that various modifications may be resorted to without departing from the spirit and intent of my invention in this respect. Thus by way of illustration, in Fig. 3, the use of keys is dispensed with by making the eccentric bearing with recesses 10, into which fit ribs 11, in the seat 6, so that the sleeve and eccentric bearing will rotate together while the eccentric bearing is free to adapt itself to the inclination of the shaft. It will thus be seen that a distinguishing characteristic of my invention consists in making the eccentric bearing for the lower end of the shaft rotatable with the sleeve in which it is mounted by means which allow said eccentric bearing to adapt itself freely to variations in inclination of said shaft.

What I claim as my invention and desire to secure by Letters Patent is,

1. In crushing mechanism of the character designated, the combination of a gyratory shaft, an upper bearing for the same,

- a sleeve, an eccentric bearing for the lower portion of said shaft mounted in said sleeve, interlocking means which insure the positive rotation of said eccentric bearing with the sleeve while permitting the eccentric bearing to adapt itself axially to the inclination of the shaft, and means for rotating said sleeve and eccentric bearing, for the purpose described.
- 10 2. In crushing mechanism of the character designated, the combination of a gyroscopic shaft, an upper bearing for the same, means for adjusting said upper bearing vertically, a sleeve, an eccentric bearing for the lower portion of the shaft mounted in said sleeve, interlocking means which insure the positive rotation of said eccentric bearing with the sleeve while permitting the eccentric bearing to adapt itself axially to the inclination of the shaft, and means for rotating said sleeve and eccentric bearing for the purpose described.
- 15 3. In crushing mechanism of the character designated, the combination of a gyroscopic shaft, means for supporting the same, a sleeve, an eccentric bearing for the lower portion of said shaft mounted in said sleeve, interlocking means which insure the positive rotation of said eccentric bearing with the sleeve while permitting the eccentric bearing to adapt itself axially to the inclination of the shaft, and means for rotating said sleeve and eccentric bearing for the purpose described.
- 20 4. In crushing mechanism of the character designated, the combination of a gyroscopic shaft, means for supporting the same, an eccentric bearing for the lower end of the shaft, said eccentric bearing being free to adapt itself to the inclination of the shaft, and interlocking means for rotating said eccentric bearing, for the purpose described.
- 25 5. In crushing mechanism of the character designated, the combination of a gyroscopic shaft, an upper bearing for the same, an eccentric bearing for the lower portion of the shaft, said eccentric bearing having an axially convex surface, a rotatable sleeve formed with a concavity in which the eccentric bearing is seated, means for preventing the movement transversely of the eccentric bearing within its seat while allowing it to adapt itself axially to the inclination of the shaft, and means for rotating said sleeve.
- 30 6. In crushing mechanism of the character designated, the combination of a gyroscopic shaft, an eccentric bearing for the lower portion of the shaft, said eccentric bearing having an axially convex surface, a rotatable sleeve formed of a plurality of parts with opposed concavity in which the eccentric bearing is seated, means for securing the parts of the sleeve together, means
- for preventing the movement transversely of the eccentric bearing within its seat while allowing it to adapt itself axially to the inclination of the shaft, and means for rotating said sleeve, for the purpose described.
7. In crushing mechanism of the character designated, the combination of a gyroscopic shaft, an upper bearing for the same, an eccentric bearing for the lower portion of said shaft, said eccentric bearing having an axially convex surface, a rotatable sleeve formed with a concavity in which the eccentric bearing is seated, the said eccentric bearing and the said sleeve being formed with axially arranged interlocking parts which insure their rotation together while allowing the eccentric bearing to adapt itself to the inclination of the shaft, and means for rotating said sleeve, for the purpose described.
8. In crushing mechanism of the character designated, the combination of a gyroscopic shaft, means for supporting the same, a sleeve, an eccentric bearing for the lower portion of said shaft mounted in said sleeve, interlocking means which insure the positive rotation of said eccentric bearing with the sleeve while permitting the eccentric bearing to adapt itself axially to the inclination of the shaft, and means for rotating said sleeve and eccentric bearing, for the purpose described.
9. In crushing mechanism of the character designated, the combination of a gyroscopic shaft, means for supporting said shaft and adjusting it on its longitudinal axis, a sleeve, an eccentric bearing for the lower portion of the shaft mounted in said sleeve, interlocking means which insure the positive rotation of said eccentric bearing with the sleeve while permitting the eccentric bearing to adapt itself axially to the inclination of the shaft, and means for rotating the sleeve.
10. In crushing mechanism of the character designated, the combination of a gyroscopic shaft, means for supporting said shaft and adjusting it longitudinally, an eccentric bearing for the lower portion of said shaft, said eccentric bearing having an axially convex surface, a rotatable sleeve formed with a concavity in which the eccentric bearing is seated, the said eccentric bearing and the said sleeve being formed with axially arranged interlocking parts which insure their rotation together while allowing the eccentric bearing to adapt itself to the inclination of the shaft, and means for rotating said sleeve, for the purpose described.
